(57) **CLAIM**

The ornamental design for a carburetor float bowl, substantially as shown and described.

DESCRIPTION

FIG. 1 is a perspective view of a carburetor float bowl showing my new design.

FIG. 2 is a front elevation view thereof.

FIG. 3 is a right side elevation view thereof.

FIG. 4 is a left side elevation view thereof.

FIG. 5 is a rear elevation view thereof.

FIG. 6 is a bottom view thereof; and,

FIG. 7 is a top view thereof.

The broken lines shown throughout the drawing are for illustrative purposes only and form no part of the claimed design.
